UNITED STATES PATENT OFFICE.

ELMER E. BROWN, OF PORTLAND, MAINE.

ADJUSTABLE HORSE-BLANKET FASTENER.

SPECIFICATION forming part of Letters Patent No. 258,215, dated May 23, 1882.

Application filed March 24, 1882. (No model.)

To all whom it may concern:

Be it known that I, ELMER E. BROWN, of Portland, in the county of Cumberland and State of Maine, have invented certain new and useful Improvements in Adjustable Blanket-Fasteners; and I do hereby declare that the following is a full, clear, and exact description of the invention, that will enable others skilled in the art to which it appertains to make and use the same, reference being had to the accompanying drawings, forming a part of this specification, in which—

Figure 1 is a top plan of the fastener; Fig. 2, a detail showing a mode of connecting the fastener to the blanket; Fig. 3, a section of the same; Fig. 4, a view of horse and blanket with fastener in use.

It is the object of my invention to produce a convenient and reliable means of securing blankets upon horses. Several devices have been in use, but none have proved satisfactory. The surcingle, which has been so long employed, with its various improvements, still fails to keep the blanket in place.

My invention consists of two or more straps passing transversely under the belly of the horse and secured to both sides of the blanket. These may be made in two parts, and these parts united by means of a buckle. The transverse straps may also be connected by a strap which is capable of being lengthened and shortened and passes under the middle line of the belly from the front transverse strap to the hindmost one.

Referring to the drawings, *d d* are the transverse straps, each having at the same end a billet or piece with a buckle, by which the length of the strap *d* may be adjusted.

e is the longitudinal strap, made in two parts secured together by a buckle, and provided with loops at each end, through which the straps *d d* may be passed. The foremost of the straps *d* should be attached to the blanket just back of the shoulder of the horse and the hindmost just in front of the stifle.

Various devices might be used to connect the ends of the straps *d* to the blanket. Billets might be sewed to the blanket at the proper points on each side and the straps *d d* buckled to the blanket; or the straps *d* might be buckled to the blanket upon the off side and secured by another device upon the other side. I pre-

fer to use snaps and rings, and in the drawings the straps *d d* have at each end a spring hook or snap, *h*. To receive these snaps rings 55 are secured to the blanket at the proper points, as indicated above. (See Fig. 4.)

In attaching the rings *f* to the blanket I use a leather disk, *a*, and the plate *b*, the former being placed beneath the blanket and the latter outside it. Thus placed, the disk and plate *b* are fastened together by the screws *c c*, the heads of the latter being sunk in the disk. (See Figs. 2 and 3.) Various substitutes may be used instead of the plate *b*—such, for instance, as a plate of metal bent or looped about the ring *f*, the ends of the plate being laid flat one above the other and secured to the blanket by a single screw passing through the disk.

In operation the use of the fastener is simple. In first applying it to a blanket, the rings being properly placed, the snaps *h* are then placed in the rings upon the off side, and the blanket placed on the horse. The snap on the other end of the foremost strap *d* is then placed in the foremost ring *f* on the near side, and the length of the foremost strap may be then adjusted to the horse. The snap on the hindmost strap *d* is then connected with the rear ring *f* on the near side, and this adjusted and the strap *e* shortened or lengthened, as the size and sex of the animal may require. When thus once fitted the blanket may be unfastened from either side, the hooks or snaps being allowed to remain in the rings upon the other side, thus rendering the fastener ready for immediate use and secure from being mislaid or lost. Rings being secured to other blankets, the fastener may be used on all of them—as, for instance, upon the blanket used at night 90 and that used when driving.

This fastener can be readily adjusted to any form of horse, keeps the blanket securely in place, prevents its turning or rolling up from before or behind, and can be used when driving 95 the horse, either over or under the harness.

The straps *d d* could of course be made long enough to pass entirely around the horse outside the blanket; but this would be found not so convenient or effectual.

What I claim as my invention is—

1. An improved fastener for horse-blankets, consisting of two or more transverse straps provided with end attaching devices and a

longitudinal strap connected to said straps, the whole adapted to be applied underneath the belly of the animal and to be attached to each side of the blanket, substantially as set forth.

2. The combination, with a horse-blanket provided with suitable side receiving attachments, of the transverse straps connected by a longitudinal strap, the transverse straps provided with suitable end attaching devices, adapted to co-operate with the receiving attachments of the blanket, substantially as set forth.

3. The improved fastener for horse-blankets, consisting of the adjustable transverse straps, the adjustable longitudinal strap provided with end loops through which the transverse

straps may slide, and the end attaching devices adapted to co-operate with suitable receiving devices upon the sides of the blanket, all substantially as set forth.

4. The combination, in a fastener for horse-blankets, of the rings *f*, transverse adjustable straps *dd*, with hooks *hh*, and adjustable strap *e*, all adapted to operate substantially as set forth.

In testimony that I claim the foregoing I have hereunto set my hand this 3d day of March, 1882.

ELMER E. BROWN.
